UNITED STATES PATENT OFFICE

2,612,165

MEDICATED PACIFIER

Joseph J. Szuderski, Glendale, N. Y.

Application November 27, 1950, Serial No. 197,717

9 Claims. (Cl. 128—360)

1

This invention relates to improvements in devices for the infant and child.

An object of this invention is to provide a pacifier of special construction so as to accommodate a container which holds a substance for consumption by a child, for example medication including vitamins and others, the container being foraminous or porous and readily replaceable and the nipple being provided with a number of apertures whereby the contents of the container may be drawn therefrom while the infant or child is using the pacifier as such.

Ancillary objects and features of importance will become apparent in following the description of the illustrated form of the invention.

In the drawings:

Figure 1 is a perspective view of the device;

Figure 2 is an exploded elevational view of the device showing the component parts thereof;

Figure 3 is a sectional view taken substantially on the line 3—3 of Figure 1 and in the direction of the arrows; and

Figure 4 is a transverse sectional view taken substantially on the line 4—4 of Figure 3 and in the direction of the arrows.

Attention is first invited to Figure 2 where the component parts of the improved pacifier are shown separate from each other. There is a nipple 10, a guard 12, a sleeve 14, a container 16, fastening band 18, plug 20 and ring 22.

The component parts of the device are assembled as disclosed best in Figure 3. The nipple 10 is disposed on the outside surface of the sleeve 14, the outside surface of this sleeve being provided with circumferential teeth 30 which constitute a means of releasably holding the tube at its open inner end on the sleeve 14. The nipple 10 has bead 32 provided at its open end for strength of construction.

There are a number of openings 34 provided in the nipple at the end thereof which is normally inserted in the mouth of the child or infant.

The guard 12 has a central opening 36 of a size sufficient to allow it to be pushed over the outside surface of the nipple 10 and yet, the aperture 36 is not so large as to allow the guard to be readily separated from the nipple.

There is a pair of notches 38 and 40 provided in the side wall of the sleeve 14 in order to accommodate the ends of the ring 22. The ring is standard in construction and function.

The plug 20 has a narrowed lower end for facility in rotating it and a threaded shank 42 which is removably disposed in threads 43. The threads 43 are formed in the bore of the sleeve 14 near

2

one end thereof and the plug constitutes a closure for the open lower end of the sleeve 14.

The container 16, which is adapted to contain various types of medication and any other substance which the child or infant should consume, is of foraminous or porous material. The same type of paper which is employed in the make-up of a tea bag, is one specific example of the type of porous or foraminous material which may be used. Alternatively, the container 16 may be of other material for example rubber or plastic, with one or more openings provided therein.

The container 16 has an open end which is inserted over the inner end of the plug 20 and over a circumferential groove 46 formed in the plug. Then, by using the resilient band which is arranged over the part of the container on the groove 46, the container is held fixed in place on the plug inasmuch as the band 18 is of such size as to fit rather tightly in the groove 46 (Figure 3).

In operation a container 16 with a proper substance in it is inserted over the appropriate part of the plug 20. Then the resilient band 18 is placed on the container in such fashion that it becomes fitted or disposed in the groove 46.

Thereafter the container is inserted in the sleeve 14 so that a part thereof projects within the body of the nipple 10 and the plug 20 is screwed in the sleeve. With the device in this condition it is ready for use by a child or infant whereby when the child or infant sucks upon the nipple, the normal moisture involved dissolves the material in the container 16. When a liquid is used in the container 16, the container may be made of gelatin, as are capsules which are designed to be taken by adults or children, the capsules being of the type whereby the casing dissolves after swallowing.

When the supply of material in the container 16 is exhausted, the container need only be replaced by a new one having more or a different substance therein.

Having described the invention, what is claimed as new is:

1. A pacifier comprising a nipple, a porous container removably disposed in said nipple and adapted to hold a substance for consumption by a child, and means securing said container in said nipple and holding said container spaced from said nipple.

2. A pacifier comprising a nipple, a porous container disposed in said nipple and adapted to hold a substance for consumption by a child, and means securing said container in said nipple, said means including a sleeve with means for

connecting said nipple to the outside surface thereof, means for retaining the container on the inside surface of said sleeve including a plug removably disposed in said sleeve and constituting a closure for said sleeve, and means to fasten said container to said plug.

3. The combination of claim 2 and said last mentioned means including a resilient band, and said plug having a circumferential groove therein within which said band is adapted to be disposed.

4. In a pacifier which includes a nipple, a container adapted to hold a substance for consumption, said container being arranged to deliver the substance therefrom, means operatively connected with said container and said nipple to hold said container within said nipple including a sleeve having a bore, means releasably securing the nipple to the outside surface of said sleeve, a part of said container being disposed in said bore, and means operatively connected with another part of said bore for holding said container secured within said bore.

5. In a pacifier which includes a nipple, a container adapted to hold a substance for consumption, said container being arranged to deliver the substance therefrom and means operatively connected with said container and said nipple to hold said container within said nipple, said means including a member having circumferential teeth on the outside surface thereof and a part of the nipple located on said circumferential teeth, and a guard disposed on said nipple and located above said teeth whereby the guard is held frictionally on the nipple.

6. In a pacifying device, a nipple, a container adapted to hold a substance for consumption, said container being so constructed as to deliver the substance therefrom, said container being

located at least in part within the nipple, means releasably retaining said container within said nipple, including a rigid member disposed in said nipple, an element removably disposed in said

5 rigid member, said element having a groove therein, a part of said container being disposed above said groove, and means removably disposed in said groove fastening a part of said container to said element.

10 7. The combination of claim 6 and a part of the outside surface of said nipple constituting a means for holding a guard removably secured to said nipple.

8. In a pacifying device, a nipple, a container 15 adapted to hold a substance for consumption, said container being so constructed as to allow delivery of the substance therefrom and being located at least part within the nipple, means retaining said container in said nipple.

20 9. A pacifier comprising a nipple, a porous container disposed in said nipple, means securing said container in said nipple in spaced relationship to the walls of the nipple, and said container being adapted to hold a substance for consumption 25 by a child.
